CLAIM

The ornamental design for a hose reel cart with utility tray, as shown and described.

DESCRIPTION

FIG. 1 is a rear perspective view of the hose reel cart with utility tray of the instant invention. The broken line showing of the inlet and outlet hoses are for illustrative purposes only and form no part of the claimed design;

FIG. 2 is a front perspective view of the hose reel cart with utility tray of the instant invention;

FIG. 3 is front elevation view thereof;

FIG. 4 is a rear elevation view thereof;

FIG. 5 is a left elevation thereof;

FIG. 6 is a right elevation view thereof;

FIG. 7 is a top plan view thereof; and,

FIG. 8 is a bottom plan view thereof.
